COMBINED BARBECUE MEAT COOKER AND BUN TOASTER

Frederick F. Gunther, Chicago, Ill., assignor to Helmeo, Inc., Chicago, Ill., a corporation of Illinois

Application January 17, 1952, Serial No. 18,105

Term of patent 14 years

(Cl. D81—10)

To all whom it may concern:

Be it known that I, Frederick F. Gunther, a citizen of the United States and a resident of the city of Chicago, in the county of Cook and State of Illinois, have invented a new, original, and ornamental Design for a Combined Barbecue Meat Cooker and Bun Toaster, of which the following is a specification, reference being had to the accompanying drawings, forming a part thereof.

In the drawing:

I claim:

The ornamental design for a combined barbecue meat cooker and bun toaster, as shown and described.

FREDERICK F. GUNTHNER.
